UNITED STATES PATENT OFFICE.

FRED A. RUMNEY, OF EAST SOMERVILLE, MASSACHUSETTS, ASSIGNOR TO UNITED SHOE MACHINERY COMPANY, OF PATERSON, NEW JERSEY, A CORPORATION OF NEW JERSEY.

MACHINE FOR MARKING SHOE-UPPERS.

989,058.

Specification of Letters Patent. Patented Apr. 11, 1911.

Application filed January 29, 1902. Serial No. 91,774.

To all whom it may concern:

Be it known that I, FRED A. RUMNEY, a citizen of the United States, residing at East Somerville, in the county of Middlesex 5 and State of Massachusetts, have invented certain new and useful Improvements in Machines for Marking Shoe-Uppers; and I do hereby declare the following to be a full, clear, and exact description of the invention, 10 such as will enable others skilled in the art to which it appertains to make and use the same.

The present invention relates to a machine for marking shoe uppers to indicate the 15 points at which the eyelets are to be attached thereto.

The object of the invention is to provide a machine by which that portion of the upper known in the art as the quarter can be 20 readily and accurately marked, so as to enable the eyeleting machine operator to set the eyelets in the proper position thereon.

With this object in view, my invention consists in the devices and combinations of 25 devices hereinafter described and claimed, the advantages of which will be obvious to those skilled in the art from the following description when read in connection with the accompanying drawings, in which—

30 Figure 1 is a view in side elevation of a machine for marking shoe uppers embodying my invention in the best form at present known to me; Fig. 2 is a view illustrating a central longitudinal section of the upper 35 portion of the machine, the lower portion being shown in elevation; Fig. 3 is a front view; Fig. 4 is a plan view of that portion of a shoe upper known as the quarter, the projecting lining which has been sewed 40 thereto being indicated in dotted lines and also the eyelets for one side of the quarter; Fig. 5 is a view similar to Fig. 4 showing the quarter folded and in condition to be inserted in the machine shown in Figs. 1, 2, 45 and 3; Fig. 6 is a detail plan view illustrating the arrangement of the gages of the machine shown in Figs. 1, 2, and 3 and the manner in which two of the gages determine 50 the position of the quarter with relation to the marking device; and Figs. 7 and 8 are detail views illustrating the construction and arrangement of the vamp markers with which the machine shown in Figs. 1, 2, and 55 3 is preferably provided.

In the manufacture of shoes the eyelets are

attached to the quarter after the two sides of the quarter, the lining, and the facing strips have been sewed together and in the case of men's shoes after the lacing hooks have been attached. A quarter for a man's shoe as it 60 appears prior to the eyeleting operation is indicated in full lines at 1 in Fig. 4, the projecting lining being indicated by dotted lines. The lacing hooks are indicated at 2 and the eyelets which are to be attached to 65 the left side of the quarter are indicated at 3 in dotted lines. In the eyelet-setting operation, the eyelets are first set successively in the right-hand side of the quarter beginning with the lowermost eyelet and then in 70 the left-hand side of the quarter beginning with the highest eyelet. It is of the utmost importance that the lowest eyelet on each side of the quarter be set at a certain distance from the lower edge of the quarter, as 75 these eyelets determine the position of the quarter with relation to the vamp in the completed shoe, and if either eyelet is located too near the lower edge of the quarter the quarter will not extend beneath the 80 vamp a sufficient distance to enable it to be sewed thereto. It is also desirable that the lowest eyelet on each side of the quarter be located the same distance from the upper edge of the quarter as otherwise one side of 85 the quarter will be higher than the other in the completed shoe.

Heretofore the points at which the eyelets are to be attached to the quarter have usually been determined as follows:—The eyeleting machine operator holds the quarter wrongside up and forces it against a pricking point secured to the work support of the eyeleting machine and thus indicates the point at which the lowermost eyelet of the 90 right-hand side of the upper is to be attached. She then places the quarter in the eyeleting machine with the marked point beneath the eyeleting devices and throws the machine into operation. The machine automatically feeds the quarter and sets the eyelets successively upon the right-hand side 95 of the quarter. The operator then removes the quarter from the machine and folds one side over the other so that the upper and lacing slit edges of the two sides coincide. She then marks the position for the highest and lowest eyelets on the left-hand side of the quarter through the highest and lowest eyelets which have been attached to the 100 105 110

right-hand side of the quarter, and places the quarter in the machine with the point which has been marked upon the left-hand side to indicate the position of the highest eyelet beneath the eyeleting devices and again throws the machine into operation, the eyelets being attached successively beginning with the highest eyelet. In order to cause the eyelets to be set at the proper points on the quarter by thus marking the quarter, considerable skill and experience is required, as the position of the lowest eyelet on the right-hand side of the quarter is marked with the quarter wrongside up, and while the lower edge of the quarter is concealed by the lining and facing strip. Although the two sides of the quarter are cut to the same shape and size originally, the lacing slit edges are seldom, if ever, of the same length when the quarter is in condition to have the eyelets attached thereto, the two sides being unequally stretched during the sewing operation. The right-hand side of the quarter which is the side which is first marked and eyeleted is usually the longer and it sometimes happens for this reason that although the positions for the lowest eyelet on the right-hand side of the quarter and for the highest eyelet on the left-hand side of the quarter are properly marked, the position for the lowest eyelet on the left-hand side of the quarter is marked too near the lower edge.

In order to enable the quarter to be readily and accurately marked to enable the eyeleting machine operator to set the eyelets in the proper position thereon and especially the lowest eyelets on each side of the quarter, my invention contemplates providing a machine comprising a marking device with gages for the lower and lacing slit edges of the quarter to determine the proper position of the quarter with relation to the marking device. The marking device is preferably arranged to mark both sides of the quarter, folded as shown in Fig. 5 of the drawing, at one operation, and the gages are preferably arranged to engage the lacing slit edges of the folded quarter and the lower edge of the left-hand side of the quarter, respectively.

My invention also contemplates providing a machine comprising a marking device with gages for the lower and lacing slit edges of the quarter to determine that position of the quarter with relation to the marking device in which the marking device will indicate the point at which the lowest eyelet is to be attached, and with a gage for determining that position of the quarter with relation to the marking device in which the marking device will indicate the point at which the highest eyelet is to be attached, this feature of my invention being particularly applicable to the manufacture of men's

shoes, in which the upper portion of the quarter is provided with lacing hooks instead of eyelets.

In carrying out my invention broadly considered any suitable form of marking device which will mark the quarter so as to indicate the point or points at which the eyelet or eyelets are to be secured thereto may be employed, the device which I prefer to use being an awl or punch which passes through and marks both sides of the quarter at one operation. Also, the gages may be constructed and arranged in any desired manner to enable the quarter to be properly positioned with relation to the marking device.

In Figs. 1, 2, and 3 of the drawings which illustrate a machine embodying a preferred form of my invention, 4 indicates a base plate which is to be secured in any suitable manner in a vertical position upon the frame of an eyeleting machine, or upon any suitable support. In lugs projecting from the lower end of the plate 4 is pivotally mounted a rod 5 so as to be capable of an oscillating movement toward and from the plate. A marking device 6 herein shown as a pointed awl, is secured to the upper end of the rod 5 by means of the set-screw 7. A sleeve 8 surrounds the enlarged upper portion of the rod 5 and projects beyond the same and into the plane of or beyond the point of the marking device 6. The upper end of the sleeve 8 is closed except for a central aperture 9 through which the marking device passes. The lower end of the sleeve is provided with an internal screw-thread which is engaged by an externally screw-threaded sleeve 10 freely rotatable and longitudinally movable upon the rod 5 below the enlarged upper portion thereof. A coiled spring 11 surrounds the marking device 6 and is interposed between the upper end of the sleeve 8 and the shouldered upper end of the rod 5. This spring normally holds the sleeve 8 in the position shown in Fig. 2 with relation to the rod 5, the upward movement of the sleeve under the force of the spring being limited by the contact of the sleeve 10 with the shoulder formed by the enlarged upper portion of the rod. By rotating the sleeve 10 in the sleeve 8 the sleeve 8 may be raised or lowered and the surface at the upper end of the sleeve adjusted with relation to the point of the marking device as may be desired. The sleeve is locked in adjusted position by means of the locking nut 12.

A block 13 is mounted upon the sleeve 8 and is supported thereon by means of a block 14 which is pivotally connected to the block and to the upper end of the plate 4. The upper end of the block 13 is provided with an overhanging portion, the lower surface 15 of which is located above the mark-

ing device 6 and the upper end of sleeve 8 and forms a work support which supports the quarter against the thrust of the marking device 6. The link 14 is pressed upon 5 by the upper end of a leaf-spring 16, the tendency of which is to swing the link outwardly upon its pivot into the position indicated in Figs. 1 and 2. The outward swinging movement of the link 14 is limited 10 by the contact of its beveled end 17 with the plate 4.

The normal position of the parts so far described is that shown in Figs. 1 and 2. In operation the quarter to be marked, folded as indicated in Fig. 5, is placed between the upper end of the sleeve 8 and the work supporting surface 15, the position of the quarter being determined by means of gages to be hereinafter described. The block 13 20 is then pressed toward the plate 4 thereby swinging the rod 5 upon its pivot. During the movement of the block 13 toward the plate 4, the block is moved downwardly upon the sleeve 8 until the work is firmly clamped 25 between the work supporting surface 15 and the upper end of the sleeve 8, and thereafter the sleeve 8 is depressed and the marking device 6 forced through both sides of the folded quarter. After the quarter has been 30 marked the parts are allowed to return to the position shown in Figs. 1 and 2 by gravity and by the force of the spring 16.

The gages which I have provided for determining the position of the quarter with 35 relation to the marking device are indicated at 18, 19, and 20. Of these gages gage 18 is an edge gage and is arranged to engage the lacing slit edges of the folded quarter. This gage is adjustably mounted in the block 40 13 at the rear of the work supporting surface 15 and sleeve 8. The gage 19 as shown consists of a rod adjustably secured in the block 13 above the work supporting surface 15, and projects horizontally therefrom, and 45 then downwardly so that its lower end is slightly below the work supporting surface 15. This gage is arranged to engage the lower edge of the left-hand side of the folded quarter, which side is uppermost when 50 the quarter is placed in the machine. The gage 20 consists of a rod adjustably secured to the block 13 below and to the rear of the upper end of the sleeve 8. This rod extends horizontally, then vertically, then horizontally, 55 tally in a plane above the work supporting surface 15, and then toward the front of the machine. The arrangement of the gages and the manner in which they determine the position of the quarter with relation to the 60 marking device will be understood from an inspection of Fig. 6. Before being inserted in the machine, the quarter is folded as shown in Fig. 5, the top and lacing slit edges coinciding. The quarter is then placed 65 in the machine as indicated in Fig. 6, the

gage 18 engaging the lacing slit edges of the folded quarter and the gage 19 engaging the lower edge of the upper side of the quarter which is the left side in the completed shoe. The position of the quarter is 70

thus determined by the gages 18 and 19 and when the marking device passes through the two sides of the quarter the marks produced on both sides will be at equal distances from the upper edge of the quarter. They will 75

also be located at the proper distances from the lacing slit edges and at sufficient distances from the lower edge of the quarter to enable the vamp to be secured thereto. In the quarter 80

shown in the drawings the right-hand side is shown as somewhat longer than the left-hand side. It will be evident, however, that the position for the lowest eyelet on each side of the quarter will be properly indicated since the gage 19 engages the lower 85

edge of the shorter side of the quarter. When the quarter thus marked is placed in the eyeleting machine with the mark indicating the position of the lowest eyelet on the right-hand side of the quarter beneath 90

the eyeleting devices and the machine is thrown into operation, the lowest eyelet will be set in proper position and the other eyelets at uniform distances therefrom. In eye- 95

leting the left-hand side of the upper the highest eyelet will be set first, and the mark which indicates the proper position of the lowermost eyelet will enable the operator to manipulate the quarter if necessary so as to cause the lowermost eyelet to be set in this 100

position. The lowest eyelet on each side of the quarter will, therefore, be set at equal distances from the upper edge of the quarter, and at a distance from the lower edge of the quarter which has been determined by the 105 gage 19 of the marking device.

If it is desired to mark both sides of the quarter at the same distance from the lower edge, the quarter instead of being folded as shown in Fig. 5 may be folded with the 110

lacing slit edges and the lower edges coinciding before being inserted in the machine, and after being so folded the sides of the quarter may be stretched to cause the upper edges to coincide. When the quarter is so 115 folded and stretched the marks produced on both sides of the quarter will be at equal distances from the lower edge as well as from the upper edge of the quarter.

If it is desired to mark the quarter to indicate the proper position for the upper eyelets, the folded quarter after having been marked to indicate the position of the lowest eyelet is moved to the left as viewed in Fig. 120

6 until the gage 20 which extends over the quarter registers with the mark which indicates the position of the lowest eyelet. The quarter will then be in a position in which the marking device will mark the 125 quarter to indicate the position of the high- 130

est eyelet, since the gage is set at a distance from the marking device equal to the distance between the first and last eyelets.

In the manufacture of ladies' shoes in which the highest eyelet is near the upper edge of the quarter, the gage 20 will not ordinarily be employed, the position of the highest eyelet on the left-hand side of the quarter being more easily determined from the upper edge of the quarter. The gage 20 is, however, of great value in the manufacture of men's shoes in which the upper portion of the quarter is provided with lacing hooks. In such shoes the highest eyelet is at a considerable distance from the upper edge of the quarter, and its position cannot be determined therefrom. By the use of the gage 20 both sides of the quarter can be marked to indicate the position of the highest eyelet.

The marking device 6 is preferably so arranged that its point indents and penetrates both sides of the quarter and thereby produces marks which can be easily distinguished. To vary the distance to which the marking device penetrates the quarter, the rod 5 is adjusted longitudinally. To allow it to be so adjusted the lower end of the rod passes through the pivot pin 21 which is journaled in the lugs projecting from the lower end of the plate 4, and a set screw 22 is provided which secures the rod to the pivot pin.

It will be noted that the work is firmly clamped between the upper end of the sleeve 8 and the work supporting surface 15 before the marking device penetrates the work, and that the marking device is withdrawn from the work before the sleeve 8 and work supporting surface 15 are separated to release the work. All danger of marring the work by bringing it into contact with the point of the marking device 6 in placing it in the machine or removing it therefrom is therefore avoided.

In addition to the features above described, the machine shown in the drawings may be and preferably is provided with devices for marking the quarter to indicate the position of the vamp thereon, whereby the vamp can be readily and accurately applied to the quarter during the vamping operation at the proper distance from the lowest eyelets. These marking devices which may be termed vamp markers consist of indenting edges or projections 23 and 24 upon blocks 25 and 26 secured in guideways in the work supporting surface 15 and the upper surface of the sleeve 8. See Figs. 7 and 8. The projections 23 and 24 are arranged in opposition to each other and act to indent the sides of the quarter at the proper distance below the marks which indicate the position of the lowest eyelets. In order to enable the vamp markers to be adjusted to vary the dis-

tance of the marks produced thereby from the lowest eyelets, the blocks 25 and 26 are adjustably secured in their guideways by means of set-screws passing through slots in the blocks.

By the use of the invention above described an unskilled operator is enabled to rapidly and accurately mark a shoe upper to indicate the points at which the eyelets are to be attached thereto. By folding the quarter before marking either side the operator is able to determine whether the sides are of the same length and can either stretch the shorter side or place the quarter in the marking machine with the lower edge of the shorter side beneath or against the gage 19, so that the mark which indicates the position of the lowest eyelet on the shorter side will be at the proper distance from the lower edge. Furthermore, the marking operation is performed while the lower edge of the quarter is in full view of the operator who is thus enabled to determine with accuracy the position of the mark. The mark for the lowest eyelet on each side of the quarter and if desired the mark for the highest eyelet on each side is produced before the quarter is placed in the eyeleting machine, so that no marking operation is required during the eyeleting operation and the quarter can be marked by a separate operator if desired.

Having thus indicated the nature and scope of my invention, and having specifically described the machine embodying a preferred form thereof, I claim as new and desire to secure by Letters Patent of the United States—

1. A machine for marking shoe uppers, having, in combination, a work support, a marking device for indicating the position of one or more of the eyelets, a gage arranged to engage the lacing slit edges of a folded quarter, and a gage arranged to engage the lower edge of the shorter side of the quarter while the sides of the quarter are in contact with each other and while the lacing slit edges of the quarter are against said first mentioned gage, said marking device and work support being relatively movable to cause the marking device to mark both sides of the quarter while positioned by said gages, substantially as described.

2. A machine for marking shoe uppers, having, in combination, a marking device and a work support relatively movable to cause the marking device to mark the work, gages for the lower and lacing slit edges of the quarter to determine that position of the quarter in which the marking device will indicate the position of the lowest eyelet and a gage for determining another position of the quarter in which said marking device will indicate the position of the highest eyelet, said gages being arranged to allow the quarter to be moved from one position to the

other without being removed from between the marking device and work support, substantially as described.

3. A machine for marking shoe uppers, having, in combination, a work support, a marking device for indicating the position of one or more of the eyelets, a gage arranged to engage the lacing slit edges of a folded quarter, and a gage arranged to entitle 10 gage the lower edge of the upper side of the quarter while the sides of the quarter are in contact with each other and while the lacing slit edges of the quarter are against said first mentioned gage, said marking device and work support being relatively movable to cause the marking device to mark both sides of the quarter while positioned by said gages, substantially as described.

4. A machine for marking shoe uppers, having, in combination, a pivotally mounted rod, a block mounted to slide thereon, a marking device for indicating the position of one or more of the eyelets secured to one of said parts, a work support carried by the other part, said work support and marking device being arranged to provide a passage-way to receive the quarter open at the front and on both sides of the marking device, and means for imparting a sliding movement to 25 the block when the rod is oscillated, substantially as described.

5. A machine for marking shoe uppers, having, in combination, a pivotally mounted rod, a block mounted to slide thereon, a marking device for indicating the position of one or more of the eyelets secured to one of said parts, a work support carried by the other part, means for imparting a sliding movement to the block when the rod is oscillated, and means for relatively adjusting the rod and block, substantially as described.

6. A machine for marking shoe uppers, having, in combination, a marking device for indicating the position of one or more of the eyelets, a pivotally mounted rod to which the marking device is secured, a block mounted to slide on said rod provided with a work support and a pivotally mounted link pivoted to the block, said work support and marking device being arranged to provide a passage-way to receive the quarter open at the front and on both sides of the marking device, substantially as described.

7. A machine for marking shoe uppers, having, in combination, a marking device for indicating the position of one or more of the eyelets, a pivotally mounted rod to which the marking device is secured, a block mounted to slide on said rod provided with a work support, means for imparting a sliding movement to the block when the rod is oscillated, and means for adjusting the rod toward and from the work support, substantially as described.

8. A machine for marking shoe uppers,

having, in combination, a marking device, a pivotally mounted rod to which the marking device is secured, a block mounted to slide on said rod provided with a work support, a spring-pressed sleeve surrounding the rod and projecting beyond the marking device, means for adjusting the sleeve, and means for imparting a sliding movement to said block when the rod is oscillated, substantially as described.

9. A machine for marking shoe uppers, having, in combination, a marking device, a pivotally mounted rod to which the marking device is secured, a block mounted to slide on said rod provided with a work support, a spring-pressed sleeve surrounding the rod and projecting beyond the marking device, and means for imparting a sliding movement to said block when the rod is oscillated, substantially as described.

10. A machine for marking shoe uppers, having, in combination, a pivotally mounted rod, a block mounted to slide thereon, a marking device for indicating the position of one or more of the eyelets secured to one of said parts, a work support carried by the other part, means for imparting a sliding movement to the block when the rod is oscillated, and gages for the lower and lacing slit edges of the quarter secured to said block to determine the position of the quarter with relation to the marking device, substantially as described.

11. A machine for making shoe uppers, having, in combination, a marking device to indicate the position of the lowest eyelet on each side of a folded quarter, a spring-pressed sleeve surrounding the marking device, a work support, and marking devices mounted on the sleeve and work support to indicate the position of the vamp on each side of the quarter, substantially as described.

12. A machine for marking shoe uppers, having, in combination, a marking device to indicate the position of the lowest eyelet on the quarter, gages to determine the position of the quarter with relation to said marking device, and a marking device to indicate the position of the vamp on the quarter while the quarter is in the position determined by said gages, substantially as described.

13. A machine for marking shoe uppers, having, in combination, a marking device to indicate the position of the lowest eyelet on each side of a folded quarter, gages for the lower and lacing slit edges of the quarter to determine the position of the quarter with relation to said marking device, and marking devices to indicate the position of the vamp on each side of the quarter while the quarter is in the position determined by said gages, substantially as described.

14. A machine for marking shoe uppers, having, in combination, a marking device to

indicate the position of the lowest eyelet on the quarter, and a marking device arranged to indicate the position of the vamp on the quarter while the quarter is in position to be acted upon by said first-mentioned marking device, substantially as described.

15. A machine for marking shoe uppers, having, in combination, a marking device for indicating the position of one or more of the eyelets on the quarter, a work support, and a yielding clamping device extending beyond the marking device, said work support and marking device being relatively movable to cause the marking device to mark the quarter, substantially as described.

16. A machine for marking shoe uppers, having, in combination, a marking device for indicating the position of one or more of the eyelets on the quarter, a work support, a gage for determining the position of the quarter with relation to the marking device, and a yielding clamping device extending beyond the marking device, said work support and marking device being relatively movable to cause the marking device to mark the quarter, substantially as described.

17. A machine for marking shoe uppers, having, in combination, a movable work support, a marking device for indicating the position of one or more of the eyelets on the quarter mounted to move with the work support, a yielding clamping device extending beyond the marking device, and means for relatively actuating the work support and

marking device to mark the quarter during the movement of the work support, substantially as described.

18. A machine for marking shoe uppers, having, in combination, a movable work support, a marking device for indicating the position of one or more of the eyelets on the quarter mounted to move with the work support, said work support and marking device being arranged to allow the quarter to be placed between them, and means for relatively actuating the work support and the marking device to mark the quarter during the movement of the work support, substantially as described.

19. A machine for marking shoe uppers, having, in combination, a movable work support, a marking device for indicating the position of one or more of the eyelets on the quarter mounted to move with the work support, a gage for determining the position of the quarter with relation to the marking device mounted to move with the work support and marking device, and means for relatively actuating the work support and marking device to mark the work during the movement of the work support, substantially as described.

In testimony whereof I affix my signature, in presence of two witnesses.

FRED A. RUMNEY.
